UNITED STATES PATENT OFFICE

2,393,294

INDEXING MECHANISM

John Crane, Palmer, Mass., assignor to Self-Locking Carton Co., Chicago, Ill., a corporation of Illinois

Application May 8, 1943, Serial No. 486,158

12 Claims. (Cl. 74—24)

This invention relates to improvements in indexing mechanisms generally. More particularly, it pertains to an indexing mechanism which performs a cycle of motions wherein a rotatable indexed member is reciprocated in a manner co-operatively to become associated with an indexing means which simultaneously imparts thereto a rotatory step-by-step advance indexing motion.

While the present invention contemplates various applications of such an indexing mechanism, it has particular reference to the use of such a device in connection with the manufacture of molded paper pulp articles, such as, for example, molded paper pulp egg cartons. In this field the success of the present invention already has been particularly significant.

Briefly, molded pulp articles, such as those indicated, may be made, for example, by horizontally rotating a cylinder of generally octagonal cross section in a solution of paper pulp. On the flat surfaces of the cylinder are secured perforated forming dies which, as they rotate through the pulp solution, suck up a controlled amount of macerated pulp, thereafter transfer the formed soggy mass to a heated pressure die which subsequently transfers it to a drying equipment.

The present indexing mechanism admirably meets the requirements necessary to perform this cycle of motions which, specifically, includes a forward motion, a backward motion, and a motion of indexing or partial rotation of the cylinder consecutively to present new surfaces or flat sections of an entire surface with each consecutive cycle.

A general object of the invention, therefore, is the provision of an improved indexing mechanism which is economic of manufacture and positive in operation, simple yet sturdy and durable of construction, and which will operate with freedom from mechanical as well as other difficulties and disadvantages.

Specific objects of the invention are the provision of an indexing mechanism which has the ability to index and register heavy parts with comparative safety at speeds faster than has been usual; which provides an accurate registered position from the completion of each indexing motion until the beginning of the next consecutive indexing motion; in which no cessation, or idle time of reciprocation, is required for time to index, the indexing taking place during the time occupied by reciprocation and allowing a full cycle for reciprocation which permits more cycles in a given time at an allowable velocity of mov-

ing parts; wherein the peak load or strain of indexing takes place at time of zero load of reciprocation, and the peak load of reciprocation occurs at the time of zero load of indexing evenly to distribute loads on driving parts; in which there are no abrupt or heavy peak loads because all actuating mechanisms are blended and harmonic, in which there is no liability of overriding of parts as with pawl and ratchet or similar mechanism due to tendency of parts in motion to keep on moving; and, in which all parts are maintained under positive control and the possibility of missing of an indexing motion is eliminated.

Other objects of the invention will in part be obvious and will in part appear hereinafter.

The invention accordingly comprises the features of construction, the combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a side elevational view, partly in section and with parts broken away, illustrating a preferred form of an indexing mechanism contemplated by the present invention in an initial stage of operation;

Fig. 2 is a plan view of Fig. 1;

Fig. 3 is a view similar to Fig. 1 illustrating an advanced arrangement of structure depicting an intermediate stage of operation;

Fig. 4 is another view similar to Fig. 1 further illustrating a continuing re-arrangement of parts exemplified by another intermediate stage of operation; and

Fig. 5 is also a view similar to the preceding elevational views showing a final stage of a completed cycle of operation and consequent relative position of parts.

Referring more particularly to Fig. 1 of the drawings there is shown a rotatable indexed member which preferably consists of a disk or end plate 10. This member is mounted to rotate with a shaft 11 journaled in a bearing header 12. For convenience in illustration there is also shown a cylinder 13 mounted on the shaft 11 and which is octagonal in its cross sectional area. Such a cylinder is representative of the type utilized in connection with the manufacture of molded pulp articles as hereinbefore briefly described. The

header 12 is slidably mounted upon a shaft 14, at the end of which there is fixed, in any suitable manner, a type of locking member or cylinder registering block 15. Projecting from one side of the rotatable member or disk 10 are spaced apart index elements or fingers 16 which preferably carry rollers 17.

At a convenient distance from the plate 10 is mounted an eccentric device generally indicated at 18 mounted upon a shaft 19. One part of the eccentric 18 consists of a disk 20 having projecting therefrom a bearing pin 21 and this constitutes a reciprocating crank. The pin 21 carries connected thereto one end of an adjustable cylinder reciprocating bar 22, the other end of which is connected to the sliding header 12 in any suitable manner as by a wrist pin 23 passing therethrough and through a lug 24 at the bottom of the header. The other part of the eccentric consists of another disk 25 carrying a pin 26 and this constitutes an indexing crank. Connected at one end to the pin 26 in an adjustable indexing connecting bar 27, the other end of which is connected to one leg of an indexing bell crank lever 28 by means of a pin 29. The bell crank lever 25 is pivoted on a shaft 30. The other leg 31 is connected to an indexing slide 32 by an index slide connecting bar 33 by means of pins 34 and 35. The index slide 32 is mounted on an index slide bar 36 and has a bifurcated indexing yoke or fork 37. The combined eccentric 18 is driven by any suitable source of power (not shown) through a gear 38 mounted upon the shaft 19. It should be noted that the combination of the two eccentric cranks are set at 90° apart so that when one is most active the other is inactive.

In performing the cycle of motions heretofore referred to as including a forward motion, a backward motion and a motion of indexing or partial rotation to present consecutively new surfaces or sections of an entire surface with each consecutive cycle, the operation is as follows:

Beginning with the initial position at zero degrees, as set forth in the arrangement in Fig. 1, the shaft 19 rotates clockwise carrying with it the eccentric device 18, the reciprocating crank and indexing crank being spaced apart 90° as above indicated. In this initial position it will be noted that the reciprocating bar 22 has already moved the rotatable member 10 and its associated parts halfway back along one stroke (to the left) in the cycle of reciprocation to a point where one of the rollers begins to enter the index yoke or fork 37 of the index slide 32. By the time the shaft 19 has continued to rotate clockwise another quarter turn, or through an angle of 90°, the rotatable indexed member 10 will have been carried to its full back reciprocating stroke. The indexing slide member continuously receives the rollers 17 within the fork or yoke 37 until the indexing slide has reached a halfway up position as indicated in Fig. 3, being actuated by the indexing connecting bar 27 operating the bell crank lever 28 and index slide connecting bar 33. During the time the shaft 19 is completing one-half a revolution, or passing through an angle of 180°, the eccentric cranks are again actuated to bring the rotatable indexed member 10 halfway forward along the reciprocating stroke in the opposite direction (to the right) and the index fork 37 will have reached the top of its upward stroke. It will be noted that through this half cycle the roller 17 has penetrated the depth of the fork 37, been carried around the fixed locking or registering cylinder block 15 and been

deposited at a point above the block 15 as seen in Fig. 4. As the shaft continues to rotate through the third quarter of its revolution to complete its travel through the next 90° to complete a total of 270° through the third quarter of revolution, the eccentric crank carrying the reciprocating bar 22 will return the rotatable indexed member 10 to its extreme forward position (to the right) being guided in register by means of the roll above and the roll below the fixed registering block 15, completing the reciprocating cycle and at this point the other eccentric crank will have carried the indexing slide, by means of the indexing connecting bar 27 and bell crank with associated parts, downwardly to a halfway down position behind the block 15 as indicated in Fig. 5. As the shaft 19 continues to rotate through the remaining 90° to complete a single revolution, it will have restored all of the parts to the position indicated in Fig. 1.

In running through this cycle of motions it will be noted that the spaced apart index elements or rollers 17 on the rotatable index member 10, and other associated parts, have been reciprocated into and out of operative position by means of the reciprocating bar and that the indexing means comprising the indexing fork 37, have been actuated by the eccentric 25 and its associated parts, consecutively to receive each of the indexing elements and rotatably advance the indexed member in a step-by-step manner consecutively and continuously during each cycle of reciprocation.

The foregoing indexing mechanism when associated with a cylinder such as that indicated at 13 and carrying suitable dies rotating in a bath of paper pulp solution, will suck up a controlled portion of the pulp and hold the same thus until the cylinder 13 moves to the forward end of the reciprocating stroke (or to the extreme right looking at the drawings and as indicated in Fig. 5) whereupon the resulting formed carton is transferred to other mechanism for ultimate finishing purposes.

It will be understood that the machine has many other advantages in addition to those appearing herein. For example, the true motion of the indexing or partial rotation of the cylinder in being accelerated from zero at the start of the cycle to its maximum rate of rotation at the middle of the indexing motion (see Figs. 1 and 3) and the deceleration from the middle to the end of the indexing operation (see Figs. 3 and 4) is not impaired by the action of the reciprocation and this acceleration and deceleration is about the easiest motion known.

In addition to this advantage it will readily be appreciated that by changing the timing position of the cranks the indexing can be made to operate in an opposite direction.

Another advantage is that by changing the position of the bell crank lever indexing can be performed at the opposite end of the reciprocation.

In addition to the foregoing advantages, other advantages will be seen in that the mechanism can be operated horizontally, as herein illustrated, or vertically or at an angle provided that the direction of reciprocation and the direction of the indexing slide are at right angles to each other. That is, the relative position of the means to accomplish the results contemplated by the present invention should be such that the slidably actuated indexing slide traverses the path of reciprocation of the rotatable indexed member, substantially as herein illustrated.

It will also become apparent that all of the functional means designed to obtain this cycle of motions can be secured without the necessity of resorting to the specific structure as shown. For example, it is of particular significance and advantage that two main shafts can be used geared together with a ratio, for example, of one to one, if the first shaft is positioned as illustrated and if the second shaft is approximately directly below or above the vertical indexing slide. Thus, the bell crank could be eliminated.

It will thus be seen that the objects and advantages hereinbefore set forth can readily and efficiently be attained and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. An indexing mechanism, which comprises in combination a rotatable indexed member, means for reciprocating said member into and out of operative position, and means for rotatably indexing said indexed member in a step-by-step manner continuously and uninterruptedly during and intermediate the limits of each cycle of reciprocation.

2. An indexing mechanism, which comprises in combination a rotatable indexed member having spaced apart index elements, means for reciprocating said member into and out of operative position, and indexing means for consecutively receiving said index elements and rotatably indexing said indexed member in a step-by-step manner continuously during and intermediate the limits of each cycle of reciprocation.

3. An indexing mechanism, which comprises in combination a rotatable indexed member having spaced apart index elements, means for reciprocating said member into and out of operative position, and indexing means comprising an indexing fork for consecutively receiving said indexing elements and rotatably indexing said indexed member continuously during and intermediate the limits of each cycle of reciprocation.

4. An indexing mechanism, which comprises in combination a rotatable indexed member having spaced apart index fingers, means for reciprocating said member into and out of operative position, and indexing means comprising an indexing yoke slidably mounted and actuated to traverse the path of reciprocation of said rotatable indexed member, said yoke intermittently receiving said index fingers consecutively and rotatably advancing said indexed member continuously during each cycle of reciprocation.

5. An indexing mechanism, which comprises in combination a rotatable indexed member having spaced apart index elements, means for reciprocating said member into and out of operative position, and an indexing sliding member comprising an indexing fork actuated by means of an eccentrically operated bell crank lever connected to said sliding member, said fork traversing the path of reciprocation of said rotatable indexed

member consecutively to receive said index elements and rotatably advancing said indexed member in a step-by-step manner continuously during each cycle of reciprocation.

6. An indexing mechanism, which comprises in combination a rotatable indexed member, means for reciprocating said member into and out of operative position, and means for rotatably advancing said indexed member in a step-by-step manner continuously and uninterruptedly during each cycle of reciprocation, both of said means being actuated by eccentrics spaced to operate substantially ninety degrees apart.

7. An indexing mechanism which comprises in combination a rotatable indexed member having spaced apart index elements, means for reciprocating said member into and out of operative position, a fixed registering member, and indexing means for consecutively receiving said index elements and rotatably advancing said indexed member by passing each index element individually across said registering member continuously during each cycle of reciprocation.

8. An indexing mechanism, which comprises in combination a rotatable indexed structure carrying spaced apart index projection elements, slidably actuated indexing means for consecutively receiving said index elements to rotate said indexed structure, and means for reciprocating said index projection elements into and out of engagement with said indexing means, and means for actuating said indexing means in synchronism with said reciprocating means to rotatably index said structure during the cycle of reciprocation of said elements and intermediate the limits of said cycle.

9. An indexing mechanism, which comprises in combination a rotatable indexed member, means for reciprocating said member into and out of operative position and indexing means for rotatably advancing said indexed member in a step-by-step manner continuously during each cycle of reciprocation, said reciprocating means including a rotatory eccentric member connected to a slidable header carrying said rotatable indexed member to a point where minimum strain imparted by the reciprocating action blends with the maximum strain of the indexing action equally to distribute the combined strains of said actions to all associated driving parts.

10. An indexing mechanism, which comprises in combination a rotatable indexed member, means for reciprocating said member into and out of operative position and indexing means for rotatably advancing said indexed member in a step-by-step manner continuously during each cycle of reciprocation, said indexing means including a rotatory eccentric member connected to a slidable indexing member to transfer the latter to an operating point where minimum strain of the indexing action blends with the maximum strain of the reciprocating action equally to distribute combined strains of said actions to all associated driving parts.

11. An indexing mechanism, comprising a reciprocable indexing member, a support reciprocable in a path at an angle to the reciprocatory path of the indexing member, an indexed member rotatably carried by said support for reciprocation therewith, means for simultaneously reciprocating said support and said indexing member in said respective paths, and coacting drive elements carried by said indexing member and said rotatable indexed member, said respective elements traversing intersecting paths and driv-

ingly engaging one another during at least a portion of the reciprocatory cycles of said members to rotatively index said indexed member.

12. An indexing mechanism, comprising a reciprocal indexing member, a support reciprocal in a path at an angle to the reciprocatory path of the indexing member, an indexed member rotatably carried by said support for reciprocation therewith, means for simultaneously reciprocating said support and said indexing member in said respective paths, coacting drive ele-

ments carried by said indexing member and said rotatable indexed member, said respective elements traversing intersecting paths and drivingly engaging one another during at least a portion of the reciprocatory cycles of said members to rotatively index said indexed member, and means coacting with the drive element on said rotatable indexed member to restrain rotation of the latter during another portion of the reciprocatory cycle thereof.

JOHN CRANE.
